CARRYING CARTON

William F. Forster, Chicago, Ill., assignor to Atlas Brewing Company, Chicago, Ill., a corporation of Illinois

Application January 29, 1936, Serial No. 61,285

12 Claims. (Cl. 229—15)

The present invention relates to carrying cartons and more particularly to the construction of a carrying carton for hand carriage of articles of manufacture or merchandise, such for example as bottled goods.

For the purpose of convenience herein, the carrying carton of the present invention will be sometimes referred to herein as a "tote" box.

There are on the market at the present time, tote boxes for like purposes wherein such a box is provided with a slidable partition member having a handle projectable through a slot in the box cover to provide means for carrying the box and its contents. Usually such boxes are made of fiber board, straw board or like material and the tendency, in such boxes when carried and supporting the entire weight of the box and its contents on the handle and its integral partition, for the partition member to force the cover outwardly from closed position and oftentimes completely opening the cover spilling the contents of such boxes.

An object of the present invention is to provide a tote box of the character mentioned wherein displacement of the cover from closed position, due to the lifting and carrying of such box, is prevented.

Another object of the present invention is to provide a tote box having a cover, with flaps for underlying the cover when closed, which flaps are hinged to the box in angular relation to the cover hinge, in order to transmit the lifting load of the box to the box in a plane defined by the hinges of the cover and flaps and thereby prevent any tendency of the cover to open. That is to say, the lifting load is applied to the box in a plane which is substantially perpendicular to the direction of lift.

A further object of the present invention is to provide, in a tote box of the character mentioned, flaps underlying the cover to provide bearing surfaces along the handle to prevent its bending or tilting toward the cover hinge, when the box is lifted by the handle, and thereby prevent displacement of the cover from closed position.

Another and further object of the present invention is to provide, in a tote box adapted for containing articles of merchandise, such as bottled goods, and wherein a shiftable partition member provides compartments for the goods and at the same time is fashioned with a handle which projects through the cover of the box when closed for carrying purposes, with means, such as flaps, underlying the cover, when closed, so that the lifting load is transmitted to the box in more

than one direction, to thereby prevent accidental displacement of the cover from closed position incidental to carrying the box.

The above, other and further objects of the present invention will be readily understood from the following description and accompanying drawings.

An embodiment of the present invention is illustrated in the accompanying drawings, and the views thereof are as follows:

Figure 1 is an isometric view of a carrying carton, or tote box, with the cover in closed position and the handle projected for carrying purposes, constructed in accordance with the principles of the present invention.

Figure 2 is a vertical sectional view through the box of Figure 1, taken substantially in the plane indicated by line II—II of Figure 1, showing in full lines the partition nested or within the box, and in dotted lines, the position occupied by the partition when it is raised to project the handle for carrying purposes.

Figure 3 is a horizontal sectional view taken between the inside of the cover, when in closed position, and the flaps, as indicated by line III—III of Figure 2.

Figure 4 is a fragmental vertical sectional view through a box somewhat similar to the present invention, and showing the tendency to open the cover flaps when the partition is raised to project the handle for carrying purposes, and showing the partition member slightly canted within the box.

Figure 5 is an isometric view of the box of the present invention with the flaps and cover opened, and the partition member in its lowermost or nested position.

Figure 6 is an enlarged sectional view taken substantially along the angular line VI—VI of Figure 1, showing the relationship of certain of the parts when the box is closed and the handle projected for carrying purposes.

The drawings will now be explained.

The form of carrying carton, or tote box, chosen to illustrate the present invention is herein shown as substantially rectangular with side walls 1, 2, 3, and 4, a bottom 5 and a cover 6 which is formed as an integral part of the side wall 4 and hinged to it by means of a crease 7 between them. The margin of the cover 6 opposite to its hinge is provided with a tuck-in flap 8 scored along line 9 to fold for tucking inside the opposite side wall 2, as illustrated in Figures 1 and 2.

The cover 6 is provided with an elongated slot 55

18 for a purpose to be later explained. The slot 19, is, in its length, provided with finger enlargements 11.

In order to divide the interior of the box into a plurality of compartments, a shiftable partition member A is provided. In the present instance this partition member comprises a longitudinally extending vertical, multi-ply fiber structure 12 and a plurality of longitudinally spaced cross members 13 defining a plurality of compartments B within the box. Formed as an integral part of the central member 12, of the partition member, is a handle 14a having a suitable cutout 15a through which the fingers of a person may pass for carrying the box. The overall height of the partition member and handle 14 is such that, when the cover is closed and the partition member nested against the bottom 5 of the box, the upper margin of the handle will be substantially flush, more or less, with the cover 6.

To receive the cross members 13 of the shiftable partition member A, the longitudinal member 12 thereof is provided with a plurality of narrow slots extending upwardly from its bottom edge. The slots extend part way of the height of the member 12 and are in width such as to tightly receive the cross members 13. Every cross member 13 has a similar slot extending downwardly from its top edge. The lengths 20 of the slots in the members 12 and 13 is such that when the cross members 13 are assembled on the member 12, the top and bottom edges of the cross members 13 will be substantially flush with the corresponding edges of the member 12.

The width of the slots being substantially the same, or slightly less than, the thickness of the interfitting parts, squeezing action takes place and thus the cross members 13 are connected to 40 the member 12 with sufficient tightness to transmit the lift from the member 12 to the cross members 13.

As the box is herein illustrated, the member 12 of the partition extends lengthwise of the box 45 so that consequently the handle 14a extends lengthwise of the box. The slot 19 in the cover, therefore, extends lengthwise of the cover.

Hingedly connected to the side walls 1 and 3 are flaps 14 and 15 respectively. These flaps are 50 scored adjacent the side walls 1 and 3 to hinge from the position shown in Figure 5, open position, to closed position or folded position, such as is illustrated in Figure 3. The length of these flaps may be substantially half, or slightly less 55 than half, the length of the box. Each of the flaps 14 and 15 is provided with a slot 16 through which the handle 14a projects. The slots 16 in the flaps 14 and 15 bear against the side margins of the handle 14a affording additional bearing surface for the sides of the handle. The provision of the slotted flaps, as mentioned, provides guideways for the handle so that the bearing surfaces of the sides of the handle against the side margins of the slots 16 as well as against 65 the side margins of the slot 19 in the cover 6, serve to prevent the handle bending or tilting when the box is grasped by the handle and lifted for carrying purposes. As a result, therefore, the handle is not bent or tilted, nor is the partition member tilted, thus preventing displacement of the cover 6 from its closed position.

By reason of the fact that the flaps 14 and 15 are hingedly connected to certain side walls of the box body in right-angular relationship to 75 the hinge of the cover 6, the hinges of the flaps

and cover define a plane which is perpendicular to the height of the box so that all of the lifting load is transmitted to the box against such plane in such a manner that the lifting load is so evenly distributed against the under surfaces of the flaps 14 and 15 that there is no tendency present for displacing the cover 6 from its closed position.

The lifting load of the box bears against the flaps 14 and 15 adjacent the hinge connections 10 thereof with their respective side walls and also against the cover 6 along its hinge connection with its side wall 4. The angular relationship of the hinge connections of the flaps and cover therefore prevents any tendency to apply the lifting load to the flaps and cover in any other than a truly vertical direction. This feature spreads the lifting load over a considerable area, equalizing it, and thus affording a tote box or carrying carton in which there is no danger whatsoever of accidentally displacing the cover from closed position, incidental to carrying the box by its handle.

Figure 5 illustrates the box of the present invention open ready to receive its contents, such as bottles. In this condition the partition member is nested or lowered against the bottom 5 of the box, the flaps and cover open, ready to receive the box contents. Where such contents consist of bottles, the bottles are inserted in the 30 various compartments B, the flaps 14 and 15 are then folded to overlie the interior of the box, the cover 6 is then folded over the flaps and the tuck-in flap 8 tucked in between the inner surface of the side wall 2 and the adjacent margins 35 of the flaps 14 and 15, thus closing the box.

The box is now ready to be carried.

When carried, a person inserts a finger through the enlargements 11 of the slot 19 of the cover and pulls up the handle 14a to project it through the slot 19 in the cover. Such upward movement of the handle raises the partition member so that the upper margins of the cross members 13 of the partition member bear against the under sides of the flaps 14 and 15 and the central or longitudinal member 12 of the partition member bears against the flaps lengthwise of the same. Such arrangement transmits the lifting load to the flaps 14 and 15 throughout an extended surface. The extremities of the cross members 13 of the partition member, adjacent the side wall 4 of the box, bear against the flaps 14 and 15 adjacent the hinge connection of the cover 6 to its side wall 4. The extremities of the central member 12 of the partition member bear against the under surfaces of the flaps 14 and 15 adjacent the hinges of these flaps to their side walls 1 and 3, thus transmitting the lifting load to the hinge connections of the flaps and cover and distributing such load over an extensive surface. The result is that when the box is lifted the lifting load is distributed equally throughout the surfaces of the flaps 14 and 15 and no displacement of the cover from closed position is possible.

Figure 4 illustrates the action of a box in which the flaps 14 and 15 are omitted.

It may be readily seen, from an inspection of Figure 4, that when a lifting load is applied to the handle 17 of the partition member, designated generally at C, the cross members 18 of such partition member bear against the inside of the cover 6a adjacent its hinge 19 thus tending to tilt the partition member C and bending the handle 17. Such tilting of the partition member tends to kick out the cover 6a from its fully closed position,

as may be seen in Figure 4, with the result that if the load be heavy there is a probability that the cover 6a may be entirely opened and the contents or at least some of the contents of the box 5 spilled out accidentally.

Referring to Figure 6 the distribution of the lifting load against the flaps 14 and 15 is readily apparent. In this figure it may be observed that the upper margins of the cross members 13 of 10 the partition member bear throughout their length against the under surfaces of the flaps so that there is no tendency to displace the cover 6 from its fully closed position.

The box as illustrated is preferably made of 15 fiber board, straw board, or like material, preferably from a single sheet of such material, suitably cut and folded to provide the box illustrated and described. In order to complete the body, a side wall, such as the wall 3 has a short end 20 flap 20 which bears against the adjacent inside surface of the wall 4 and is thereto suitably secured, as by stitching, stapling or the like.

The carrying carton of the present invention is one that may be manufactured economically 25 and is one which possesses sufficient strength for the purpose intended and at the same time affords a convenient carrying carton or tote box for articles of merchandise, such for example as bottled goods.

30 The invention has been described herein more or less precisely as to details, yet it is to be understood that the invention is not to be limited thereby, as changes may be made in the arrangement and proportion of parts, and equivalents may be 35 substituted, without departing from the spirit and scope of the invention.

The invention is claimed as follows:

1. A hand carrying carton for merchandise comprising a box having side walls, a bottom, and 40 a cover hinged to one side wall to complete the closure; a partition member within said box of less height than the box and having a carrying handle as a part thereof; said cover having a slot through which said handle projects when said 45 partition member is raised; and flaps hinged to certain of the side walls of the box adapted to lie between said partition member and cover to relieve said cover from displacement forces when said box is carried by said handle.

50 2. In a merchandise carrier of the type wherein a shiftable partition member has a handle projectable through the carrier cover to carry the carrier, flap means hinged to certain of the carrier walls to underlie the cover when closed and adapted to be contacted by the partition member 55 to apply lifting forces to the carrier in such manner as to prevent displacement of said cover by such forces.

3. In a merchandise carrier of the type wherein 60 a shiftable partition member within the carrier has a handle projectable through a slot in the carrier cover to permit totage of the carrier, flap means hinged to certain walls of the carrier to lie between said partition member and cover 65 when the cover is closed to spread the lifting load over a substantial surface and to prevent displacement of the cover from closed position.

4. In a carrying carton of the type wherein a shiftable partition member has a handle projectable through the carton cover to carry the carton, flap means hinged to certain of the carton walls to underlie the cover when closed and adapted to be contacted by the partition member, said flap means having slots for the handle 70 to extend the surface contact of said flap means

with the handle to prevent tilting of the handle and consequent opening hinging action of the cover.

5. A tote box having a hinged cover provided with a slot, handle means nested within said box 5 and projectable through the cover slot for carrying purposes, and slotted flaps adjacent the sides of said handle when projected to prevent tilting of the handle to open the cover.

6. A carrying carton comprising a box having 10 a cover hinged to one side wall, flaps right-angularly hinged to certain of the side walls of the box and foldable underneath said cover when the cover is in closed position, a partition member 15 within said box having a handle, the member and handle being of less height than the box, said flaps and cover being slotted to receive said handle when it is projected for carrying purposes, said partition member when raised bearing against said flaps in extended surface engagement, the angular hinging of said flaps with respect to the hinge of said cover transmitting the lifting load to the cover in extended surface contact to thereby prevent accidental opening of 20 the cover. 25

7. A carrying carton including a cover hinged to a side wall of the carton and slotted to receive a handle, flaps hinged to side walls of the carton in right-angular relationship to the cover hinge and foldable underneath the cover, means shiftable within the carton providing a handle projectable through the cover slot, said flaps having slots to receive the projected handle and afford bearing surface along the handle to prevent the handle from tilting toward the cover hinge to 35 displace the cover from its closed position when the handle is grasped to carry the carton. 30

8. A carrying carton including a cover hinged to a side wall of the carton and slotted to receive a handle, flaps hinged to the side walls of the 40 carton in right-angular relationship to the cover hinge and foldable underneath the cover, means within said carton providing a handle projectable through the cover slot, said flaps serving to maintain the plane of the handle within the plane of the vertical axis of the carton and thereby transmit the lifting load against the flaps and cover in a direction perpendicular to a plane defined by the hinges of the cover and flaps. 45

9. A carrying carton including a cover hinged to a side wall of the carton and having a slot to receive a handle, flaps hinged to the side walls of the carton in right-angular relationship to the cover hinge and foldable underneath the cover, a shiftable partition member within the carton having a handle projectable through the cover slot for carrying purposes, said partition member engaging against said flaps when said handle is projected, the right-angular relationship of the flap and cover hinges defining a plane perpendicular to the lifting effort and against which the load is applied to prevent displacement of the cover from closed position when the carton is lifted by the handle. 50 55 60

10. In a carrying carton of the class described, a hinged cover for the carton, means within the carton shiftable toward and away from said cover and having a projectable part to provide a carrying handle, and flaps hinged to two opposite 70 side walls of the carton and foldable to overlie said shiftable means and engageable by said means when shifted to carrying position to transmit the carrying load of said carton to said means through said flaps. 75

11. In a carrying carton of the class described, a hinged cover for the carton, means within the carton shiftable toward and away from said cover and having a projectable part to provide a carrying handle, and flaps hinged to two opposite side walls of the carton, said means adapted to contact said flaps with lifting action adjacent their hinged connections to said side walls when said flaps are folded to overlie said shiftable means to thereby transmit the carrying load of said carton to said means at such contacts and relieve the said cover of lifting strain.

12. In a carrying carton of the class described, a hinged cover for the carton, separate partition means within the carton shiftable toward and away from said cover and having a projectable part to provide a carrying handle, and means other than said cover contacted by said shiftable partition means when shifted to carrying position to take the lifting load of said carton when the carton is lifted by the handle of the shiftable partition member.
